(57) **CLAIM**

I claim the ornamental design for a tag for electrical plug, as shown and described.

DESCRIPTION

FIG. 1 is a top perspective view of a tag for electrical plug showing my new design, the bottom perspective view being a mirror image thereof;

FIG. 2 is a top plan view thereof;

FIG. 3 is a front elevation view thereof;

FIG. 4 is a bottom plan view thereof;

FIG. 5 is a rear elevation view thereof;

FIG. 6 is a right side elevation view thereof; and,

FIG. 7 is a left side elevation view thereof.

The broken lines in the drawings depict portions of the tag for electrical plug that form no part of the claimed design. The dash-dot-dash lines define the boundaries of the claim.
